UNITED STATES PATENT OFFICE.

JOHN C. WAHL, OF CHICAGO, ILLINOIS, ASSIGNOR, BY MESNE ASSIGNMENTS, TO
REMINGTON ACCOUNTING MACHINE CORPORATION, OF NEW YORK, N. Y., A
CORPORATION OF NEW YORK.

CALCULATING-MACHINE.

1,397,188.

Specification of Letters Patent. Patented Nov. 15, 1921.

Application filed June 6, 1912. Serial No. 702,053.

To all whom it may concern:

Be it known that I, JOHN C. WAHL, a citizen of the United States, residing at Chicago, in the county of Cook and State 5 of Illinois, have invented certain new and useful Improvements in Calculating-Machines, of which the following is a specification.

My invention is an improvement in calculating machines.

It has for its object the construction of a machine which will be able to calculate totals of quite a variety of forms.

More specifically stated, one part of my 15 invention is a machine that will be able to add and subtract numbers placed upon a sheet of paper whether in vertical, that is columnar, or in horizontal, that is linear, arrangement, or in both. Another part of 20 my invention is the construction of a machine that will be able to calculate simultaneously, the totals of various columns of numbers and will simultaneously calculate the grand total of said totals.

25 The invention is illustrated by the drawings forming part of the application. Of such drawings Figure 1 shows a front elevation of the calculating machine and of a portion of the typewriter whereon it is 30 mounted. The covers are shown so as to give a picture of the parts as viewed by the operator.

Fig. 2 is another elevation of the same 35 parts and differs from Fig. 1 principally in the fact that the covers have been removed. It does not show all of the parts as that would be unnecessary.

Fig. 3 is a plan of the top of the actuator and immediately beneath the totalizer.

40 Figs. 4 and 5 are front elevations showing some of the parts in their various operating positions.

Fig. 6 is an end elevation taken along the plane 6—6 of Fig. 1. Similarly Figs. 45 7 and 8 are respectively taken along the planes 7—7 and 8—8 of Fig. 1.

The calculating machine described in this application may be considered an extension and outgrowth of the one now on the market in connection with the Remington typewriter and which is described in several 50 patents, particularly in Patent No. 893,719 issued to me July 21, 1908. Reference is had to said patent for the detailed description of the parts.

For the understanding of this invention it is sufficient to recall that in the machine as at present on the market, there is mounted upon the framing 1, of the typewriter, an actuator 2, which is connected by means of links 3 to the numeral key levers 100 of the typewriter. The depressing of any of the key levers and consequent operating of this connecting link 3, results, by a mechanism described in said patent, in the vibration of a digit shaft 4, to an amount dependent upon and corresponding to the value of the numeral key depressed. The depressing of any of the key levers 100 results also in the operating of a universal 70 rock shaft, 5. By the coöperation of the digit shaft 4, and the rock shaft 5, there is given to the sector 6, which is mounted thereon, a movement about to be described. The sector 6 is mounted upon the digit shaft 75 4 so as to rotate therewith, but is also able to swing about an axis which is perpendicular to the axis of the shaft 4. Normally the sector 6 stands in an inclined non-operating position as shown in the figures. By the 80 operation of the rock shaft 5 the sector is first brought into an active position with its plane perpendicular to the axis of the digit shaft 4, and is then given its movement, after the completion of which it is 85 again brought to its nonactive position. During the return of the parts to their normal positions the sector occupies its non-active position and thus does not reverse the action that it produced during its vibrating 90 in its forward movement.

The rock shaft 5, the digit shaft 4, the master dog 15 and other parts of my present machine may be variously constructed and connected as far as my present invention is 95 concerned. Suitable mechanism coöperating with these parts is shown in my Patent No. 893,719 hereinbefore referred to; also in a later patent of mine No. 1,148,732 dated August 3, 1915, more refined mechanism is 100 shown, and suitable mechanism is shown in other patents. In short, this part of the Wahl calculating machine is well known in the art.

Coöperating with the sector 6 in its active 105 position are a direct gear 7 and a reverse gear 8. The three gears, namely the sector 6, the direct gear 7 and the reverse gear 8, rotate about parallel axes. The direct gear 7 and the reverse gear 8 are always in mesh 110

with each other. To produce addition the direct gear 7 is located in a place where the sector 6 will mesh therein during its advance or operating stroke. The reverse gear 8 is 5 withdrawn to prevent interference. To produce subtraction it is the reverse gear 8 that is placed in mesh with the sector and the direct gear 7 that is withdrawn to prevent interference. This is accomplished by providing both the direct gear and the reverse gear with a lever 9, which coöperates with a groove in each one of them. The lever 9 is fulcrumed at 10 in the framing of the machine. The reverse gear 8 is provided 10 with a long shaft 11, which extends to the left and at its extreme end coöperates with the helically shaped cam slot, 12. The latter is operated by a handle 13, which forms one piece with the cam. By the proper 15 locating of said handle 13, it is evident that either the direct gear or the reverse gear may be placed in a position to coöperate with the sector 6, during its operating stroke as may be desired.

25 Splined upon the shaft whereon the direct gear 7 is mounted is the master gear 14. The direct gear 7 and the master gear 14 therefore always rotate an equal amount in the same direction. Coöperating with the master gear 14 is a master dog 15. The latter is moved through the proper intermediate mechanism which is operated by the rock shaft 5.

The master gear and master dog may 30 coöperate with the totalizer gears and totalizer chain disconnectors, as described in said Patent No. 893,719 or in my Patent No. 893,718, dated July 21, 1908. The totalizer shown in the drawings, however, has the outline of the totalizers that were being manufactured for the market at the time when the present application was filed and the construction of which can be understood from the patent to Goldberg 1,099,497, dated June 40 9, 1914. Said Goldberg patent also describes certain mechanism for computing numbers not written in the decimal system but those features of said patent are not shown in the present case. The totalizer base 16, is 45 mounted upon the totalizer bar 17. The latter is supported in the framework of the machine and connected to the carriage 18, of the typewriter, so as to move in unison therewith. The totalizer gears and totalizer 50 disconnectors are therefore carried *seriatim* through the master gear and master dog, during the operation of the machine. All 55 the above mechanism is old.

To accomplish the results desired it was 60 decided to be advisable to practically reproduce and place on the side another master couple, that is another master gear and another master dog, to coöperate with another totalizer. Moreover for convenience the latter totalizer has been made stationary and

not movable as with the totalizers coöperating with the master gear 14. To offset the stationariness of the side totalizer, 19, its coöperating master gear and master dog were made movable relatively thereto. In order 70 to distinguish clearly the master gear and master dog, which coöperate with the stationary totalizer, from the master gear and master dog which coöperate with the totalizers mounted upon the totalizer bar and which 75 travel in unison with the carriage of the typewriter, the former will be called universal and the latter columnar. The side totalizer, the side master gear and the side master dog will therefore be the universal totalizer, universal master gear and the universal master dog. The others will be the columnar totalizer, the columnar master gear and the columnar master dog. The reason 80 why the word universal has been adopted for the side totalizer is because it will be evident from the further description that it may be used universally, that is with numbers located on any portion of the paper. Further, because of the construction of this 85 machine, it can be used to obtain the total of numbers located on the paper in a column determined by the position of the totalizer upon said totalizer bar.

There will now be described the mechanism by means of which the universal master gear obtains its movement.

The direct gear 7 is in mesh with an auxiliary gear 20, which is rotatably mounted upon a stud 21 fastened in the framing 100 (Figs. 2, 4 and 5). The auxiliary gear 20 therefore always rotates in a direction dependent upon the rotation of the direct gear 7. Both rotatably and slidably mounted in the framework of the machine is a shaft 22 which ends at its extreme left in a stud 23 whereby it is laterally located, and a gear 24 rigidly fastened thereto. Somewhat to the right is another gear 25 also rigidly fastened thereto. Still farther to the right and at its extreme right portion is a long pinion, 26. The gear 24 is located in the immediate vicinity of the auxiliary gear 20 and the shaft 22 when brought to a lateral position to mesh said gear 24 and the auxiliary gear 20, will 110 be given a rotation in the same direction as the rotation of the master gear 14. The gear 25 is located in the vicinity of the master gear 14 and when properly laterally located to mesh therewith, the shaft 22 will be given 115 a rotation in the opposite direction as said master gear. Said shaft 22 is capable of being located in any of three lateral positions which I shall denominate, 1, a similar position, 2, a reverse position, and 3, a nonactive position. To bring it to any of said 120 positions the gear 25 rigidly fastened to the shaft 22 is provided with a hub which has therein a groove 27 wherein is embraced a roller 28 mounted at the end of one arm of 125 130

a lever 29, another arm of which is provided with a spring 30. The lever is fulcrumed in the framework at 31. The lever 29 is also provided with a roller 32. An examination of the drawing will show that the tension of the spring 30 tends constantly to raise the roller 32 upward, and shift the shaft 22 to the left. If the tension of the spring would be unresisted, then the shaft would be brought to its extreme position to the left, in said position the gear 25 would be in mesh with the master gear 14. Should the shaft 22 be removed from its extreme position as by the depressing of the roller 28, and be brought into its middle position then the gear 24 will be in mesh with the auxiliary gear 20. Should the shaft 22 be moved still farther to the right and be brought into its extreme right position then neither of its gears 24 or 25 will mesh with its co-operating gear, but the gear 24 will then be brought into mesh with the stationary pin 33 rigidly fastened to the framing. This will cause the locking of said gear and consequently also of the shaft 22.

The roller 32 is not the only means by which the shaft 22 may be located in either of its three positions. Another is the handle 34 which co-operates with the stud 23 at the left end of shaft 22. The handle 34 is pivotally mounted in the framing of the machine and has connected thereto a tension spring 35 which tends to pull the front part of said handle downward. This downward pull is resisted by reason of said handle engaging a ratchet rod 36. When said handle 34 is moved from its extreme left position to another position to the right, it pushes the shaft 22 along therewith, but 40. itself incapable of being pushed back to its prior position on account of the ratchet shape of the rod 36. The shaft 22 may therefore be manually located in either of its two active or in its nonactive position.

45. As previously stated the shaft 22 is provided at its extreme right end with a long pinion 26. The latter is long enough so that the lateral displacement thereof does not effect the further mechanism and said displacement may therefore be overlooked. Always in mesh with said pinion 26 is the universal master gear 37, slidably and rotatably mounted upon a shaft 38 fastened in the framework of the machine, best shown 50. in Fig. 8. The universal master gear 37 is adapted to mesh with the set of totalizer carrying gears 39, rotatably mounted upon a shaft 40 each carrying gear 39 is in mesh with an intermediate idle gear 41, which in 55. turn is in mesh with the numeral gear 42 which is provided with a set of numerals upon a cylindrical disk rigidly fastened thereto. Co-operating with the carrying gears 39 are a set of carriable gears 43, 60. mounted singly upon a set of supporting

levers 44, which levers are supported upon shafts mounted in the framework. The construction is similar to that described in connection with the columnar totalizers in the above cited patents and will therefore not be further entered upon. Attention is here recalled to the fact that preliminarily to the rotating of the universal master gear 37 there must be operated the lever 44 co-operating with the carrying gear 39, enmeshed 75 with said master gear.

The operation of the lever is brought about as follows: It has previously been mentioned that the ordinary machine as placed on the market and as described in the patents hereinbefore mentioned, is provided with a rock shaft 5. In the present machine said rock shaft has been provided at its extreme right end with a plate 45 (Fig. 7), to which is joined a link 46 at its upper end. The lower end of this link is joined to a plate 47 fulcrumed in the framing at 48. The plate 47 co-operates with two rollers, 49 and 50, fastened in a plate 51 which in turn is rigidly fastened to the left 90 side of a rock shaft 52 supported in the framing. The shaft 52 has extending therefrom at its extreme right and its extreme left, two arms, 53, in which there is mounted a roller shaft or bail bar 54. Slidably mounted upon the rock shaft 52 and a stationary shaft 57, is a small framework 55 (Fig. 2), which carries mounted therein the universal master dog 56 (Figs. 2 and 8). The latter is supported with its fulcrum upon the rock shaft 52 and embraced between the two fingers thereof is the roller shaft 54. It is however located laterally by the walls of the framework, 55. It is therefore evident that when properly laterally located the universal master dog, 56, will be operated by the movement of the rock shaft 52 and will therefore operate to disconnect the supporting lever 44, with which it may at that moment be co-operating, which was above 110 desired.

There will now be described the mechanism by means of which both the universal master gear 37, and the universal master dog 56, are given their proper lateral location simultaneously and co-operatingly. The framework 55 is supported at its lower end by the rock shaft 52 and at its upper end by the stationary shaft 57. Rigidly fastened to said framework and extending 115 therefrom to the right is a shaft 58 which is provided with rack teeth, 59, which mesh with a spur gear wheel 60, rigidly fastened to the lower end of a vertical shaft 61 and which is pivoted in the framing. The shaft 120 61 is provided at its upper end with another spur gear wheel 62 of equal size, and the latter gear wheel meshes at its front with the rack teeth 63, of a bar 64 slidably mounted within the framing and carrying exten- 130.

sion 65 upon which is mounted the master gear 37. It is thus evident that the universal master gear and the universal master dog have an equal lateral movement. The 5 parts are so shaped that both are brought into coöperation with their parts simultaneously.

The gear wheel 62 meshes at its back with another rack 66 (Fig. 3), also slidably 10 mounted in the framing of the machine. The rack is provided with a tension spring 67, which has one end fastened to the rack and the other end fastened to the framing. There is thus produced a tendency to carry 15 the latter rack, 66, to the right and therefore to move the universal master gear and master dog constantly to the left. The latter is their normal position.

The rack bar 66 is provided at its left with 20 a stud 68, whereon is pivotally mounted a hook bar 69 (Figs. 3, 4 and 5). The latter is provided with a leaf spring 70 fastened thereto and whose end rests upon an extension 71 of the rack bar 66 and the result of 25 which is that the hook bar 69 normally assumes elevated position. The hook bar 69 is provided with a hook 72 which is adapted to coöperate with an extension 73 formed upon the back lower corner of the right 30 wall of the columnar totalizer. During the operation of the machine whenever any totalizer provided with such an extension passes over said hook 72 then the latter will be engaged by the former and 35 as the totalizer moves to the left the hook will be pulled along therewith. Therefore so will also the rack bar 66. Because of the mechanism above described, the result will be that there will also be pulled 40 along, but to the right, and not to the left, both the universal master gear and universal master dog. The operating of the numeral key levers of the typewriter at this moment will therefore result in the operating of the 45 proper sections of the universal totalizer.

It is necessary that after the inserting of the lowest or units place in the totalizer, the universal master mechanism automatically return to its normal position. Said normal 50 position as above described corresponds to the highest decimal place location. In order to permit said automatic returning the hook bar 69 is provided toward its middle on its lower edge with a disconnecting incline 74. As the hook bar is pulled along to the left by any of the columnar totalizers, the incline 74 also travels to the left. Immediately after the units decimal location thereof the incline makes contact with the 55 underside of a fixed disconnecting bracket, 75, fastened to the framing of the calculating machine. The continued movement of the incline 74 therefore causes the hook bar 69 to move downwardly and to retract the 60 hook 72 from the extension 73 of the colum- 65

nar totalizer. Immediately thereupon the tension spring 67 becomes effective and returns all the parts operated thereby to their normal or highest placed positions.

It has previously been mentioned that the 70 universal totalizer can be placed in three conditions by means of the handle 34, in two of which it is active and in the third of which is nonactive. It would be superfluous as well as objectionable to permit the 75 universal master mechanism to reciprocate on account of the travel of the carriage and columnar totalizer thereon, whenever said universal totalizer is in nonactive condition. To prevent said superfluous reciprocation of 80 the master mechanism, the shaft 22 has been provided with a collar 76 (Figs. 3 and 4), which when said shaft is in its nonactive or rightmost position contacts with the left side of a lever 77 fulcrumed upon a portion 85 of the framing and having extending therefrom toward the back an arm 78 which reaches into a slot 79 formed at the left lower corner of a plate 80, slidably mounted upon the framework by means of two inclined slots 81 which embrace two studs 82 fastened in the frame work. The lever 77 is also provided with a spring 83 which tends continually to move the back end of said lever toward the right. Because of the construction of the parts this results in a tendency to move the plate 80 always to its elevated position. Formed in said plate 80 is a horizontal slot 84 with two enlarged openings, 85, one at each end of said slot. Extending through said slot is a pin 86 fastened into the hook bar 69. The parts are so dimensioned that when the plate 80 is in its elevated position, the pin 86 is sufficiently high so that the hook 72 is also sufficiently 90 elevated to be encountered and engaged by any extension 73 upon any columnar totalizer. But when the shaft 22 is shifted to its nonactive position the plate 80 is thereby depressed. Therefore so is also the pin 86 95 and also the hook 72. The hook will therefore be too low to be engaged by any columnar totalizer extension 73 which might pass over it.

It is evident that by the mechanism above 100 described the operator has at its disposal practically two calculating machines, namely the columnar calculating machine and the universal calculating machine. These might be operated for certain forms in conjunction with each other and for other forms independently of each other. Assuming that there is but one total required and that the numbers of which said total is to be the sum are arranged in a horizontal line it is evident that it would be sufficient to cause the universal master mechanism and more particularly the hook 105 72 to be engaged by the extension 73 for each one of said numbers. In this case it 110

120

125

130

would be superfluous to have said extension 73 upon the columnar totalizers as there would be no columnar total desired. For this case it has been found convenient to 5 replace the columnar totalizer by a dummy totalizer, 90, as shown in Fig. 1. The dummy totalizer contains no wheels but has means of fastening it to the totalizer bar and is provided with the extension 73. It is evident 10 that the ordinary columnar totalizers and the dummy totalizers can be mounted together upon the totalizer bar. How many 15 of each and their arrangement upon said bar will depend upon the form required.

15 In certain forms it is required to cause the universal totalizer to cooperate with the columnar totalizer in a certain predetermined manner. Thus if a number be entered into the first columnar totalizer it might 20 be desired that the same number shall enter into the universal totalizer in the same manner, say additively or subtractively in both. Again it might be required that the 25 number entering into the columnar totalizer shall enter into the universal totalizer in a reverse manner, that is if additively in the columnar totalizer then subtractively in the universal totalizer and vice versa. Again in certain cases it might be desired that the 30 number shall enter into the columnar totalizer and not enter at all in the universal totalizer. Each of these three mentioned possibilities can be brought about by the 35 manual adjustment of the handle 34. But in case this form is predetermined as it ordinarily is in commercial houses the manual adjustment is then inconvenient and an automatic mechanism is highly desirable. Such an automatic mechanism has been provided 40 in this machine. It consists of a three-level cam associated with the columnar totalizer and coöperating with the roller. Let it be recalled that the placing of said roller in its lowest position renders the universal 45 totalizer nonactive. The placing of said roller in its middle position renders the universal totalizer reverse and the placing thereof in its highest position renders it similar. To place the roller in any of said 50 positions the cam 91 accompanying the columnar totalizer is given its own proper level. In this particular case the cam extends least downward when the roller is in its highest position, the cam extends more 55 downward to cause the roller to assume its middle position, and the cam extends most downward to cause the roller to assume its lowest position. The positioning of these 60 cams over the roller therefore automatically locates the roller in the desired positions thereof and thus automatically brings the universal totalizer in its various required conditions.

It has been stated that the cam 91 is asso-

ciated with the columnar totalizer. The actual construction of this association is immaterial. What is necessary and sufficient is that the totalizer coöperate with its master mechanism simultaneously with the cam coöperating with the roller. Purely for 65 convenience however the cam has been fastened to the totalizer. The placing of the totalizer upon the totalizer bar in any desired position therefore simultaneously causes the placing of the cam in its required 70 operative position.

The cam 91 is detachably fastened to the totalizer so that any one of the three varieties of cams may be readily placed thereon.

80

In the machine on the market and described in the above mentioned patents there is found in the master mechanism, 1, a master wheel, 2, a master dog, 3, a stationary bar coöperating with the totalizer carriable gear supporting arms, 4, an aliner situated immediately to the right of the master wheel, and 5, a stationary pointer to indicate to the operator the particular decimal place of operation of the totalizer. It is of course understood that there are similar mechanisms provided for the universal master mechanism. The universal master mechanism therefore contains a moving master mechanism which is composed of, 1, a master wheel, 2, a master dog, 3, a bar coöperating with the totalizer carriable gear supporting arms, 4, and a liner situated immediately to the right of the master wheel, and 5, a pointer to indicate to the operator 95 the particular decimal place of operation of the totalizer. In other machines the master mechanism may, of course, contain elements differing more or less from those enumerated. The totality of parts associated with 100 the master wheel may be called the master group. It may therefore be said that the machine is provided with a stationary master group and also with a reciprocating master group.

110

In my pending application Sr. No. 629,308, filed May 23, 1911, there is shown a disconnect handle for preventing the operation of the master wheel by the keys, and when this handle is moved to disconnecting position it also renders inoperative the means for connecting the totalizer intermittently with the carriage. Said application contains claims on this feature broader than the claims in the present case. Said pending 115 application Sr. No. 629,308 also shows cams which travel with the typewriter carriage and which control the functions of the cross footing master wheel with respect to add, subtract and disconnect, and said application 120 contains claims on this feature broader than those contained in the present case. In that application the master wheel does not have

125

the reciprocation of the universal master wheel of the present case but is stationary with respect to right and left-hand travel.

As will be understood from Figs. 2 and 8, 5 there is a stationary notched bar 101 in the lower part of the auxiliary totalizer frame, having a notch corresponding to each of the register wheels 42; and the lower part of the master dog 56 enters one of these notches 10 when the machine is operated, thus alining the master wheel 37 with the gear 39 and locking the frame 55 against lateral movement while the master wheel is rotating. This feature is not claimed herein, but is 15 claimed in my application Sr. No. 156,009, filed March 20, 1917.

Having thus described my invention I claim:

1. In a calculating typewriting machine, 20 the combination of a paper holding carriage traveling to determine a printing point, a stationary totalizer, a reciprocatable master group adapted to coöperate with said stationary totalizer, a set of numeral keys, 25 mechanism operated by said numeral keys to determine the number inserted in the stationary totalizer by said master group, a universal member in said master group, mechanism moving said universal member 30 through a constant amount upon the operation of any of said numeral keys, mechanism to attach the reciprocatable master group to the paper holding carriage to thus cause the said group to travel in synchronism 35 with said carriage, and means to detach the reciprocatable master group from the carriage at a predetermined position.

2. In a calculating typewriting machine, 40 the combination of a paper holding carriage traveling to determine a printing point, a stationary totalizer, a reciprocatable master group including a master wheel and a master dog, said master wheel and master dog being adapted to coöperate with said 45 stationary totalizer, a set of numeral keys, mechanism connecting said master wheel and said master dog with said numeral keys, said mechanism being adapted upon the depression of any of said numeral keys to 50 move said master dog a constant amount and move said master wheel a differential amount, mechanism to attach said reciprocatable master group to said paper holding carriage to thus cause said group to travel in 55 synchronism with said carriage, and means to detach the master group from the carriage at a constant predetermined position.

3. In a calculating typewriting machine, 60 the combination of a carriage traveling to determine a printing point, a totalizer bar traveling with said carriage and adapted to support a traveling columnar totalizer, a stationary auxiliary totalizer, a set of numeral keys, a reciprocatable master group 65 adapted to coöperate with said stationary to-

talizer, said master group including a differential member and a universal member, a set of numeral keys, means to move said differential member a differential amount and said universal member a constant amount 70 upon the operation of any of the numeral keys of said group, an extension on said totalizer bar to engage said master group to thus cause the latter to travel in synchronism with the carriage, and means to detach 75 said reciprocable master group from said extension at a constant predetermined position thereof.

4. In a calculating typewriting machine, the combination of a carriage traveling to 80 determine a printing point, a totalizer bar traveling with said carriage and adapted to support a columnar totalizer, a columnar totalizer mounted on said bar, a stationary auxiliary totalizer, a reciprocatable master 85 group adapted to coöperate with the stationary totalizer, said master group including a master wheel and master dog, a set of numeral keys, means to move said master wheel a differential amount and said master dog a 90 constant amount upon the operation of any of said numeral keys, an extension on the columnar totalizer to engage the master group and thus cause the latter to travel in synchronism with the columnar totalizer, 95 and means to detach the said master group from said totalizer extension at a constant predetermined position of said extension.

5. In a calculating machine the combination of: a sector vibrating an amount dependent upon the value of the digit; a stationary master gear; a shaft on which said gear is mounted; a reciprocatable master gear; gear connections between the sector and the stationary master gear; and means 100 including change gear connections whereby said shaft drives said reciprocatable master gear in the same direction as said stationary master gear or in the opposite direction as desired. 110

6. In a calculating machine the combination of: mechanism moving an amount dependent upon the value of the digit; a stationary master wheel operated by said digit valuing mechanism; a reciprocatable master wheel also operated by said digit valuing mechanism; a primary rock shaft operated equally for every digit; a stationary master dog operated by said primary rock shaft and coöoperating with the stationary 115 master wheel; a reciprocatable master dog coöoperating with the reciprocatable master wheel and operated by; an auxiliary rock shaft; and link connections between the primary and auxiliary rock shafts. 120

7. In a calculating machine, the combination of a carriage to determine the different columns and the various decimal places of each of said columns, a columnar total calculating mechanism, a reciprocating master 125 130

- group, an auxiliary total calculating mechanism adapted to be actuated by said reciprocating master group and means to determine whether said master group shall be active or non-active in respect to said auxiliary total calculating mechanism, said means including a cam mechanism, an element of which is mounted on said carriage whereby the action or non-action of said master group 10 on said auxiliary total calculating mechanism may be predetermined for any of the columns in the travel of said carriage.
8. In a calculating machine, the combination of a carriage traveling to determine the different columns and the various decimal places of each of said columns, a columnar total calculating mechanism, an auxiliary total calculating mechanism, capable of being set into either of three conditions, the first condition causing it to calculate similarly, the second condition causing it to calculate reversely to the columnar total calculating mechanism and the third condition causing it not to calculate; a reciprocating master group including a master wheel adapted to actuate said auxiliary total calculating mechanism and a cam mechanism part of which is mounted on the carriage for determining in which of the three possible 30 conditions said auxiliary total calculating machine shall be put whereby a definite program of calculating may be predetermined for said auxiliary total calculating mechanism for the different columns in the run of said carriage.
9. In a calculating machine the combination of: a carriage traveling to determine the columnar positions of the numbers and the various decimal places of said numbers; a calculating mechanism to obtain the totals of said numbers; connecting mechanism between the carriage and the calculating mechanism and normally causing part of said calculating mechanism to reciprocate once for every number; a handle manually placeable in either of three positions in the first of which it causes the calculating mechanism to be additive, in the second subtractive and in the third nonoperative; and a disconnecting device brought into operation by said handle when in its third position and disconnecting and breaking the connection between the calculating mechanism and the carriage, whereby the rendering of said calculating mechanism nonoperative simultaneously and automatically renders its reciprocatable part nonreciprocating.
10. In a calculating machine the combination of: a carriage traveling to determine the columnar positions of the numbers and the various decimal places of said numbers; a calculating mechanism including a part normally reciprocating once for every number; a connection between the carriage and the reciprocating part of the calculating mech-
- anism; a cam traveling in unison with said carriage and having two levels, an active level which renders the calculating mechanism active, and an inactive level which renders the calculating mechanism inactive; and a disconnecting mechanism brought into operation by said cam in its inactive level to break the connection between the carriage and the reciprocatable part of the calculating mechanism whereby the rendering of the calculating mechanism inactive simultaneously and automatically renders the reciprocatable part of the calculating mechanism nonreciprocating.
11. In a calculating machine the combination of: a carriage traveling to determine the columnar positions of the numbers and the various decimal places of said numbers; a calculating mechanism including a part normally reciprocating once for every number; a connection between the carriage and the reciprocating part of the calculating mechanism; a cam having three levels in the first of which it renders the calculating mechanism additive, in the second subtractive and in the third nonactive; and a disconnecting mechanism brought into operation by said cam in its inactive level to break the connection between the carriage and the reciprocatable part of the calculating mechanism whereby the rendering of the calculating mechanism inactive simultaneously and automatically renders the reciprocatable part of the calculating mechanism nonreciprocating.
12. In a calculating machine the combination of: a carriage traveling to determine the column; a columnar master mechanism; an auxiliary linear master mechanism; a handle placeable in either of two positions, namely an active position which renders the auxiliary linear calculating mechanism active, and an inactive position which renders the auxiliary linear calculating mechanism inactive; cam mechanism part of which is mounted on the traveling carriage said cam having two levels, an active level which renders the auxiliary mechanism active, and an inactive level which renders the auxiliary mechanism inactive; an extension on the traveling carriage to engage the auxiliary master mechanism to thereby cause it to travel in unison with said carriage; and a removing mechanism for breaking the connection between the extension and the reciprocatable master mechanism said removing mechanism coöperating with both the handle and the cam mechanism and thus causing the reciprocatable auxiliary master mechanism to be not engaged by the carriage extension when either the handle or the cam mechanism is inactive.
13. In a calculating machine, the combination of: a decimal carriage; a second decimal carriage adapted to be intermittently

- connected to said first carriage and moved synchronously therewith while so connected; a connecting link mounted on one carriage; a coöperating adjustable catch mounted on the other carriage whereby said connection is established; a totalizer associated with one decimal carriage; a master mechanism for inserting numbers in said totalizer; cam-controlled determining means determining the action of said master mechanism on said totalizer; and a cam acting on said cam-controlled mechanism, said cam being connected to said adjustable catch and simultaneously adjustable therewith.
14. In a calculating machine, the combination of: a decimal carriage; a second decimal carriage adapted to be intermittently connected to said first carriage and moved synchronously therewith while so connected; a connecting link mounted on one carriage; a totalizer having a projecting catch adjustably mounted on the other carriage, said catch being adapted to coöperate with said link whereby said connection is established; a second totalizer associated with the other decimal carriage; a master mechanism for inserting numbers in said second totalizer; cam-controlled determining means determining the action of said master mechanism on said second totalizer; and a cam mounted on said first totalizer and acting on said cam-controlled mechanism whereby the adjustment of said first totalizer on its carriage will simultaneously adjust both the catch and the cam.
15. In a calculating machine, the combination of a totalizer, a moving carriage, a reciprocating master wheel for said totalizer, said wheel being adapted to be intermittently and repeatedly connected to said moving carriage during a single run thereof and thereby enable said totalizer to be brought into action in different zones of the travel of said carriage, a master wheel adapted to enter numbers into said totalizer, a gear shift device controlling the action of said master wheel and a set of adjustable cams mounted on said carriage to control the action of said gear shift device.
16. In a calculating machine, the combination of a traveling carriage, a totalizer, a reciprocating master group including a master wheel and a universal member, means to move said master wheel a differential amount and said universal member a constant amount, a gear shift device to control the action of said master wheel and leave the action of said universal member unchanged, a set of cams adjustably mounted on said traveling carriage and means controlled by said cams to control said gear shift device.
17. In a calculating machine, the combination of a set of digit keys, a traveling carriage, a computing device, a master wheel adapted to insert numbers in said computing device upon the operation of said digit keys, means to reciprocate said master wheel repeatedly relative to said computing device upon a single travel of the carriage, an escapement for said carriage also operated by said digit keys, a bar traveling synchronously with said carriage, a plurality of cams adjustably mounted on said bar, a follower cooperating with said adjustable cams and a gear shift device for said master wheel controlled by said follower, whereby the action of said digit keys on said master wheel during a single travel of the carriage may be predetermined for each of the reciprocations of said master wheel.
18. In a calculating machine, the combination of a set of digit keys, a traveling carriage, a computing device, a master wheel adapted to insert numbers in said computing device upon the operation of said digit keys, means to reciprocate said master wheel repeatedly relative to said computing device upon a single travel of the carriage, an escapement for said carriage also operated by said digit keys, a bar traveling synchronously with said carriage, a plurality of cams mounted on said bar, a follower cooperating with said cams and a gear shift device for said master wheel controlled by said follower, whereby the action of said digit keys on said master wheel during a single travel of the carriage may be predetermined for each of the reciprocations of said master wheel.
19. In a combined typewriting and calculating machine, the combination with a platen and printing mechanism, one traveling relatively to the other to write numbers in columns; and a totalizer and an actuator, one traveling past the other once for each column; of a bar; a device adjustable along said bar to determine a calculating column, said device having thereon a catch and a cam; means controlled by said catch to cause the relative travel of said totalizer and actuator for the column determined by said device; and means controlled by said cam to control the action of said actuator as to addition and subtraction.
20. In a combined typewriting and calculating machine, the combination with a platen and printing mechanism, one traveling relatively to the other to write numbers in columns, a columnar totalizer for registering the numbers written in a column, and an auxiliary totalizer and an actuator therefor, one traveling past the other once for each column; of a catch on said vertical totalizer, means controlled by said catch to cause the relative travel of said auxiliary totalizer and its actuator for the column determined by said vertical totalizer, a cam on said vertical totalizer, and means controlled by said cam to control the

action of said auxiliary actuator as to addition and subtraction.

21. In a calculating machine, the combination of a master wheel, two intermeshing gears, one of which is connected to turn said master wheel, a sector for driving said intermeshing gears alternatively, and means for shifting said intermeshing gears axially in opposite directions so that one of them is advanced toward said sector as the other is withdrawn from it.

22. In a calculating machine, the combination of a master wheel, two intermeshing gears, one of which is connected to turn said master wheel, a sector for driving said intermeshing gears alternatively, and means for shifting said intermeshing gears axially in opposite directions so that one of them is advanced toward said sector as the other is withdrawn from it, the construction being such that in one extreme position of said shifting means one of said gears is in position to mesh with said sector to drive the master wheel in one direction, in the other extreme position of said means the other gear is in position to mesh with said sector to drive the master wheel in opposite direction, whereas in the middle position both

said gears are out of range of said sector so that the master wheel is not turned. 30

23. In a calculating machine, the combination of a master wheel, two intermeshing gears, one of which is connected to drive said master wheel, a sector for alternative engagement with said intermeshing gears, 35 and shifting means including a lever of the first order connecting the two said gears to slide them axially in opposite directions, one of said gears being adapted to mesh with said sector in one extreme position of 40 said lever to drive the master wheel in one direction, the other of said gears being in position to mesh with said sector in the other extreme position of said lever to drive the master wheel in the opposite direction, 45 and both gears being out of range of said sector in the middle position of said lever so that said sector does not drive said master wheel.

In witness whereof, I have hereunto 50 signed my name, this 31st day of May, 1912.

JOHN C. WAHL.
